Attorney.

UNITED STATES PATENT OFFICE.

WILLIAM P. WALKER, OF MACON, MISSOURI.

ROOF.

SPECIFICATION forming part of Letters Patent No. 230,161, dated July 20, 1880.
Application filed May 28, 1880. (No model.).

To all whom it may concern:

Be it known that I, WILLIAM P. WALKER, a citizen of the United States, residing at Ma-
5 con, in the county of Macon and State of Mis-
souri, have invented certain new and useful
Improvements in Tin or Metal Roofing; and I
do hereby declare that the following is a full,
10 clear, and exact description of the same, refer-
ence being had to the annexed drawings, mak-
ing a part of this specification, and to the let-
ters and figures of reference marked thereon.

Figure 1 is a perspective view of my invention.
Fig. 2 is a longitudinal section of the
15 same. Fig. 3 is a plan view of the sheet-metal
blank from which the end cap is formed, and
Fig 4 is a perspective view of the cap bent into
form ready for securing in place upon the roof.

This invention has relation to certain new
20 and useful improvements in sheet-metal roof-
ing; and the object thereof is to so cover the
roof with sheet metal as to render it perfectly
wind and water tight, and at the same time
render the roofing firm and lasting, so that
25 there will be no danger of the metal sheeting
working loose and rattling, caused by the wind
getting under it.

The invention consists in the peculiar man-
ner of laying and securing the metal sheets
30 and manner of constructing the end caps which
are placed over the strips of wood, as shown
in the drawings and hereinafter described.

In the accompanying drawings, A repre-
sents a section of a roof, to which are secured
the wooden strips B, a strip of sheet metal, C,
35 being first laid upon the roof and turned up
so as to come in between the mortar and brick
of the wall when there is one upon the roof,
the purpose being to prevent leaks. The
wooden strips are then secured to the roof, be-
40 ginning with the first one, the metal plate D
at the left of the strip being turned up against
the side thereof and secured by nailing, the
metal plate at the right of the strip being simi-
larly secured in place and to the wooden strip,
45 as shown at X, Fig. 2. The wooden strips and
sheet-metal plates are thus connected to the
roof and together throughout the width of said
roof, after which flanged caps E F are slipped
over the flanges a of the plates D, and after-
50 ward bent down against the sides of the wooden

strips, as shown, respectively, in Y Z, Fig. 2,
the rear ends of the plates D and caps E be-
ing secured by solder to the sheet-metal strip
C, which prevents wind or dampness from get-
ting in and rusting the sheet metal. Where 55
these wooden strips B are used it is essential,
to successfully complete the roofing and pre-
serve the strips from the dampness, to have
them thoroughly covered and protected at
their ends. This I accomplish by forming the 60
caps F with an apron, G, having ears or flaps
b, said cap with its apron and flaps being
stamped in the form shown in Fig. 3, after
which it is bent in the form shown in Fig. 4.

After the caps E F have been secured in 65
place upon the top of the wooden strips B the
aprongs G of the caps F are nicely fitted around
the ends of said strips and nailed thereto, the
flaps b being pressed or hammered against the
sides of the wooden strips and soldered to the 70
plates D, thus forming a perfect and durable
shield for the ends of the wooden strips.

The caps E are formed with single flanges e,
while the caps F have double flanges d, these
flanges being formed by suitable machinery 75
ready to be applied to the roof.

The plates D being secured to the roof
and to the wooden strips, as illustrated at X,
Fig. 2, the edges are turned out at right an-
gles, as shown in dotted lines, after which the 80
caps E are placed over them and next the
caps F.

The advantage of having the caps F formed
with the double flanges d is that they can be
85 slid along over the flanges of the plates D, and
are securely held in place thereon while they
are being bent down, as shown at Z, Fig. 2, and
the aprongs G secured by soldering to the plates,
the caps F being completed by suitable ma-
chinery, ready to be applied to the roof, as 90
shown in Fig. 4 of the drawings.

The manner of laying the sheet-metal plates
to the roof and to the wooden strips, in con-
nection with the flanged caps, makes a very
strong and durable roofing—one that will not 95
easily become injured by heat or cold or by
severe storms, and as the metal plates and
caps are firmly connected together there is no
danger of the plates or caps working loose; and
a very essential feature of my invention is the 100

manner of shielding and protecting the ends of the wooden strips from the dampness which would tend to rot them.

Having fully described my invention, what I claim as new, and desire to secure by Letters Patent, is—

In a metallic roofing having the wooden strips B, the plates D, connected to the roof and to the strips, and having their edges turned down at right angles, in combination with the caps E, formed with flanges c, and the caps F,

formed with double flanges d, aprons G, and flaps b, the plates and caps being connected together and to the wooden strips, as specified, and for the purpose set forth.

In testimony that I claim the above I have ¹⁵ hereunto subscribed my name in the presence of two witnesses.

WILLIAM P. WALKER.
